US0D1006849S

(12) **United States Design Patent** (10) Patent No.: **US D1,006,849 S**
(45) Date of Patent: ** Dec. 5, 2023

(54) **MOBILE ROBOT BASE WITH SHELVES AND WITHOUT MAST**

- (71) Applicant: **Locus Robotics Corp.**, Wilmington, MA (US)
- (72) Inventors: **William Richardson Jones**, San Francisco, CA (US); **Colin Alexander Davis**, New Orleans, LA (US); **John Stephen Lanier**, New Orleans, LA (US); **Seth Edwards Allen**, Newton, NH (US); **Michael Sussman**, Winchester, MA (US); **Michael Charles Johnson**, Ashland, MA (US); **Sean Johnson**, Danvers, MA (US); **Brad Edward Fiore**, Vernon, CT (US); **Christina Nicole Fong**, Somerville, MA (US); **Peter Sussman**, Wilmington, MA (US)
- (73) Assignee: **Locus Robotics Corp.**, Wilmington, MA (US)
- (**) Term: **15 Years**
- (21) Appl. No.: **29/816,592**
- (22) Filed: **Nov. 23, 2021**

CLAIM

We claim the ornamental design for a mobile robot base with shelves and without mast, as shown and described.

DESCRIPTION

FIG. 1 is a top, front perspective view of a mobile robot base with shelves and without mast showing our new design; FIG. 2 is a front perspective view thereof; FIG. 3 is back perspective view thereof; FIG. 4 is a right side view thereof; FIG. 5 is a left side view thereof; FIG. 6 is a top plan view thereof; and, FIG. 7 is a bottom plan view thereof. In the drawings, the broken lines represent portions of the article which form no part of the claimed design.

1 Claim, 6 Drawing Sheets
